HENRY T. GRAF, OF BRIARCLIFF MANOR, NEW YORK.

GOLF-BAG SUPPORT.

1,170,891.

Specification of Letters Patent. Patented Feb. 8, 1916.

Application filed November 6, 1915. Serial No. 59,893.

To all whom it may concern:

Be it known that I, HENRY T. GRAF, a citizen of the United States, and resident of Briarcliff Manor, county of Westchester, and State of New York, have invented certain new and useful Improvements in Golf-Bag Supports, of which the following is a specification.

My invention relates to means for supporting the golf or caddie bag in substantially upright position when the player is making a shot so that the bag does not have to be thrown down or laid upon the ground. This enables the player to readily select and replace the club without the necessity of stooping down or lifting the bag. I accomplish this by providing the bag with a bar or bracing strip extending longitudinally thereof upon which a slide block is mounted near the top of the bag, the ordinary carrying handle of the bag being secured to the slide block instead of to the bag so that the player by manipulating the handle in lifting or setting the bag down can slide the block and operate two of the tripod legs so as to spread the same the slide block being suitably locked in the sideways.

The object of this arrangement is to provide an attachable device which may be readily attached to existing forms of golf bags without much modification thereof.

Another object is to facilitate spreading the legs by the simple operation of setting down the bag and closing the legs by the operation of lifting the bag by means of the handle.

One form of my improved device is shown in the accompanying drawings in which—

Figure 1 is a side view of the golf bag with the tripod legs spread; Fig. 2 is a rear view of the bag with the legs spread substantially as in Fig. 1; Fig. 3 is a vertical sectional view with the legs collapsed and the slide block and handle in the uppermost position; Fig. 4 is a transverse cross-section on the line 4—4 of Fig. 3.

Referring to the drawings 1 represents the usual golf or caddie bag which may be of canvas or any suitable material bound with leather at the top 2, which binding incloses a metal ring 3 for stiffening the top of the bag in the usual manner. The bottom is usually bound with leather as at 4 and is preferably fitted with a wooden base inside

of the leather bottom substantially as shown 55 at 5 in Fig. 3 of the drawings.

In carrying out my invention I preferably provide a bar 6 extending longitudinally of the bag, the lower end of the bar at 7 being bent at right angles and extending under 60 the bottom of the bag as shown in Figs. 1 and 3; the end 7 is preferably provided with a hole through which the screw 8 is passed which entering the bottom 5 of the bag is adapted to secure the lower end of the bar 6 65 in place. The upper end of the bar 6 is preferably bent over so as to close the ring 3, the bent over portion 9 extending inside the bag as shown in Fig. 3. A screw 10 is preferably provided, taking through the bar 6 just 70 below the ring 3 and extending under the ring and thereby securing the bar to the upper end of the bag. Obviously this construction may be conveniently modified to meet the requirements of different forms of 75 bag constructions. On the bar 6 I preferably at 11 secure the buckle 12 which coöperates with the carrying strap 13 in the usual manner. The buckle is usually secured to the body of the bag, but since my device is preferably attached to the rear of the bag it is desirable to secure the buckle 12 to the bar 6 instead of to the bag. The upper end of 80 the bar 6 is preferably provided with a slide-way 14 which may be of rolled or bent metal 85 or other suitable material as may be desired and may be secured to the bar 6 in any suitable manner as by rivets 15.

A slide block 16 is adapted to slide longitudinally of the ways in the slide-way 14 90 and carries on its outer surface a handle 17 which is preferably secured to the ends of a spring strip 18 extending lengthwise of the slide block 16 substantially as shown in Fig. 3 of the drawings. One end of the spring strip 95 18 is securely riveted to the slide block 16 by rivets 19, while the other end is resiliently movable and carries a bolt 20 extending through a hole in the slide block 16 and adapted to enter holes 21 or 22 in the rear plate of the slide-way 14 as indicated in Fig. 3 of the drawings. Near the lower end of the slide block 16 a transversely disposed bracket 23 is secured by rivets 24, this bracket being provided with outwardly extending 100 ears to which the tripod legs 25 are pivotally secured as indicated in the drawings, the ears of the bracket 23 preferably form an

obtuse angle to each other so that the legs 25 will swing out at an angle to each other to form a tripod in conjunction with the bar 6 as will be seen in Figs. 1 and 2 of the 5 drawings.

The lower part of each leg is connected with a link 26 pivotally connected at 27 to a bracket 28 secured to the bar 6 in such relation to the slide-way 14 that when the 10 slide block 16 is in its uppermost position the links 26 are substantially vertical and the legs are collapsed or drawn in so as to lie parallel with the bar 6 as shown in Fig. 3 of the drawings. The ears of the bracket 15 28 to which the links 26 are connected are at an angle corresponding substantially with the angle between the ears of the bracket 23 so that when the legs are spread in the 20 position shown in Figs. 1 and 2, the links act as braces for the legs 25.

The operation of my improved golf bag support is simple and should be readily understood for it will be seen that when the player is carrying his bag of clubs the parts 25 are in the position shown in Fig. 3 of the drawings. When he desires to set the bag down in order to make a shot, the bottom of the bag is placed on the ground and the lower part of the handle 17 is pulled out- 30 wardly to withdraw the bolt 20 from the upper hole 21, thus permitting the slide block 16 to be moved downward in the slide-ways. This downward movement of the slide block 16 causes the legs 25 to be moved 35 downward and the links 26 being thus thrown outward will automatically spread the legs into the position indicated in Figs. 1 and 2 of the drawings. When the slide block 16 reaches the lower end of the slide- 40 way 14, the bolt 20 will be in position to enter the hole 22 and lock the support with the pair of legs in the spread position, where they with the bar 6 will form a tripod for supporting the bag of clubs. When the 45 player has made a shot and is ready to go forward for the next shot the handle 17 is again grasped and the mere act of attempt-

ing to lift the bag will draw the bolt 20 out of the lower hole 22 and slide the block 16 to the upper end of the slide-way 14 and collapse the legs into the position shown in Fig. 3 of the drawings.

It will be understood that various modifications in the specific details of construction of my device may be made without departing from the spirit and scope of my invention.

I claim—

1. In a golf bag support the combination with a bar secured to the bag, a slide mounted thereon, a pair of tripod legs pivoted to said slide, means for locking said slide against movement and manually operated means for releasing said slide.

2. A golf bag tripod comprising a bar secured to the bag, a pair of legs, brace links connecting the legs to said bar, a slide block mounted on said bar and adapted to spread the legs and means for locking said slide block to hold the legs either collapsed or spread.

3. A golf bag tripod comprising a bar removably secured to the bag, a slide block mounted to slide longitudinally of the bar, a pair of legs pivotally carried by said slide block, links connecting the legs to said bar so as to spread the legs by sliding said block and means for locking the block.

4. In a golf bag support the combination of a bar, means for removably securing the bar to a golf bag, a slide block mounted for reciprocation longitudinally of said bar, a pair of tripod legs pivotally secured to said block and adapted to be spread by sliding said block, a handle on the block and a bolt carried by said block for locking the same against movement said handle being adapted to operate said bolt to unlock the block and slide it to spread or close the tripod legs.

In testimony whereof I have hereunto set my hand.

HENRY T. GRAF
